US00D357736S

United States Patent [19]

Dye

[11] Patent Number: Des. 357,736

[45] Date of Patent: ** Apr. 25, 1995

[54] CONNECTOR FOR DEVICE FOR APPLYING
COMPRESSIVE PRESSURE TO THE LEG

[75] Inventor: John F. Dye, Bridgewater, Mass.

[73] Assignee: The Kendall Company, Mansfield,
Mass.

[**] Term: 14 Years

[21] Appl. No.: 13,025

[22] Filed: Sep. 16, 1993

[52] U.S. Cl. D24/129; D23/260;
D24/129

CLAIM

The ornamental design for a connector for device for applying compressive pressure to the leg, as shown and described.

DESCRIPTION

FIG. 1 is a perspective view;

FIG. 2 is a top plan view;

FIG. 3 is a front elevation view;

FIG. 4 is a bottom plan view;

FIG. 5 is a side elevational view thereof, the opposite side elevational view being a mirror image thereto; and,
FIG. 6 is a back elevation view.

FIG. 1

FIG. 2

FIG. 3

FIG. 4

FIG. 5

FIG. 6
